EMIL HAEFELY, OF BASEL, SWITZERLAND, ASSIGNOR TO WESTINGHOUSE ELECTRIC
AND MANUFACTURING COMPANY, A CORPORATION OF PENNSYLVANIA.

APPARATUS FOR MANUFACTURING INSULATION.

1,171,609.

Specification of Letters Patent. Patented Feb. 15, 1916.

Application filed May 27, 1912. Serial No. 700,026.

To all whom it may concern:

Be it known that I, EMIL HAEFELY, a citizen of the Republic of Switzerland, and a resident of Basel, in Switzerland, have invented a new and useful Improvement in Apparatus for Manufacturing Insulation, of which the following is a specification.

My invention relates to apparatus for continuously treating a strip of paper or other insulating fabric and winding the same into a tubular insulating body.

The object of my invention is to provide a machine of the class above indicated that shall be relatively simple in construction and adapted to produce bodies of varying dimensions.

According to my present invention, I provide a machine which is adapted to continuously coat a strip of insulating fabric, rapidly dry the coating on the surface and finally soften the coating by the application of considerable heat just as it passes upon the mandrel on which the tubular body is produced. This apparatus has the advantage of drying off the solvent material by evaporation previous to the application of the final heat at the time the fabric is wound upon the mandrel and is, in this respect, an improvement over the apparatus shown and described in my previous Patent No. 858,386, issued to my assignee, the Westinghouse Electric & Manufacturing Company, July 2, 1907.

Furthermore, my invention combines, in a single machine, means for coating the paper or other fabric and means for manufacturing tubular bodies.

Figure 1 of the accompanying drawings, is an elevation, with certain of the parts shown in section, of a machine constructed and arranged in accordance with my invention. Figs. 2, 3 and 4 are detail views, and Figs. 5 and 6 are, respectively, a plan view and a front elevation of that portion of the machine shown in Fig. 1 in which the tubular insulating bodies are finally produced.

Referring to the drawings, the machine here shown comprises a coating section having a bed 1, and pedestals 2 and 3, and a tube-making section having posts or pedestals 4 and 5.

The coating section is provided with a plane oblique surface or table 6 having

guide rolls 7 and 8 rotatively supported at its respective ends, heating surfaces 9 and 10 and a plurality of guide rolls 11 to 16, inclusive, all of which are mounted transversely of the bed 1 and coöperate to stretch the fabric over the table 6 and the heating surfaces 9 and 10 without permitting it to be drawn over sharp corners.

A supply roll 17 of paper or other suitable fabric is mounted in bearings 18 which are secured to the pedestal 3. A bearing block 19 is forced into engagement with one end of a shaft 20 upon which the roll 17 is mounted by means of an adjustable weight 22 and its supporting lever 21. Heat is supplied to the heating surfaces 9 and 10 by means of gas flames which are fed with fuel through supply pipes 23 and 24. Since the heating surfaces and attachments are similar and may be identical, only the surface 10 and its attachments will be described in detail. The heating surface itself, over which the paper is passed, is preferably formed of sheet metal which is curved or bent as shown in Fig. 1. The area below the heating surface 10 is partially inclosed by plates 25 having flanges 26 to form a channel 27 in which a transverse section of perforated gas pipe 28, constituting the burner, is disposed.

The guide roll 16 is rotatively supported in notches 29 which are provided in a pair of uprights 30 located at one end of the bed 1. The arrangement of parts is such that the position of the roll may readily be adjusted to suit the size of the mandrel on which the fabric is wound.

The tube-making section which is shown in end elevation in Fig. 1 and is illustrated more fully in Figs. 2 to 6, inclusive, comprises an adjustable pressure member, a burner or heating mechanism, a mandrel or cylinder 31, a driving motor 32 and suitable gearing between the motor and the mandrel shaft.

The mandrel or cylinder 31 is rotatively supported in bearings 33 and 34 provided in the standards or pedestals 4 and 5.

The combined pressure member and heating apparatus comprises a frame or carriage 35 having end projections or arms 36 and 37, the arms 36 being located at the respective sides of the pedestal 4 and the

arms 37 being correspondingly located with reference to the pedestal 5. Weights 38 and 39 are connected to the arms 36 and 37 by ropes or chains 40 and 41 which extend 5 over pulleys 42 and 43 and tend to force the frame or carriage 35 in an upward direction. By this means, a pressure plate 44, which forms a part of the frame or carriage, is forced into engagement with the 10 surface of the mandrel or cylinder 31. The degree of pressure between these members is determined by a strap 45 which is yieldingly connected to the frame or carriage and a windlass 46.

15 The frame or carriage is provided with a downwardly extending cylindrical projection 47 which is centrally located and is closed at its lower end except for a small hole 48 through which a rod 49 extends, a piston or 20 head 50 is secured to the upper end of the rod 49 and operates within the member 47 against the pressure of a spring 51. The strap 45 is connected to the lower end of the rod 49 and is wrapped around the gathering 25 surface of the windlass 46.

The weights 38 and 39 are sufficiently heavy to exert an upward pressure of the frame or carriage 35 considerably in excess of that which is required in the operation 30 of the machine and, consequently, the pressure may readily be adjusted to any desired value by turning the adjusting worm 52 of the windlass by means of a hand wheel 52a.

The carriage is provided with a perforated pipe 53 which constitutes a burner, fuel being supplied to the burner through supply pipes 54 and 55, having flexible hose sections 56 and 57 in order to permit of free adjustment of the carriage. The perforations in the 35 pipe 53 are at the top, as shown in Fig. 3 of the drawings so that the gas flames play directly upon the under surface of the pressure plate 44. The plate 44 is supported by laterally perforated side bars or rails 58, and 40 the carriage is provided with flanged plates 59 between which the side bars or rails are supported upon a plurality of vertical rods 60. The rods 60 project upwardly through holes 61 in a channel beam 62, which constitutes the body of the carriage, and are provided with enlargements at their lower 45 ends which operate in cylinders 63. The cylinders 63 preferably consist of short pipe sections which are internally threaded at 50 their lower ends to receive adjusting nuts 64, springs 65 being interposed between the nuts 64 and the enlargements or heads of the plungers 60.

When the tubular insulating body is completed, as hereinafter pointed out, it may be cut into tubular members of shorter lengths by using the mandrel as the rotating member of a lathe. I have accordingly provided transverse strips or bars 66 which are supported upon the pedestals 4 and 5 by means

of hooks 67, and longitudinal beams or rods 68 which constitute a rest for a hand tool. After the tubular body has been subdivided, it may be removed from the mandrel by any suitable means.

A gear wheel 69 is secured to one end of the mandrel shaft and is operatively connected to the motor 32 by means of a pinion 70, a countershaft 71, gear wheels 72 and 73, a countershaft 74, a worm wheel 75 and a worm 76 which is mounted on the motor shaft. The gears 69 and 70 may be interchanged in position in order to drive the mandrel at a relatively high speed, for the purpose of subdividing the completed tubular body.

The operation of the machine is as follows: Assuming that a roll of paper, or other fabric, of which a tubular body is to be constructed, is mounted in the bearings 18, 85 the fabric is fed over guide roll 8, table 6, roll 7, drying surface 9, guide rolls 11, 12, and 13, drying surface 10, and guide rolls 14, 15 and 16 to the mandrel or cylinder 31.

The motor 32 is operated to slowly drive the 90 mandrel or cylinder 31 and to draw the paper, or other fabric, through the rolls and over the drying surfaces. As the paper passes slowly over the table 6, it is coated with shellac or varnish, either manually or 95 otherwise, and sufficient heat is applied to the drying surface 9 to drive off the solvent material and leave a coating of insulating gum on the surface. The drying surface 10 completely hardens the coating and drives 100 off all traces of moisture. The coated paper is then guided over rolls 15 and 16 to the mandrel or cylinder 31. The pressure plate 44, which is maintained at a relatively high temperature, is forced into engagement with 105 the paper or strip of fabric just as it is wound upon the mandrel. The heat of the surface is sufficiently great to soften the gum with which one surface of the paper is coated, and thus cause the layers of the fabric to adhere closely to form a very hard and compact tubular body of insulating material.

It will be understood by those skilled in the art that the final product is very much improved by first driving off the moisture 115 instead of attempting to exclude the moisture and soften the gum by means of a single application of heat.

The entire operation can be cared for by a single attendant and, furthermore, handling the fabric after it is coated and before it is made into the tubular body is obviated.

Structural modifications may, of course, be effected within the spirit and scope of my invention.

I claim as my invention:

1. Apparatus for manufacturing tubular bodies comprising a coating surface, a plurality of spaced drying surfaces, a forming mandrel and means for simultaneously

applying relatively high heat and pressure to a strip of fabric as it is wound upon the forming mandrel.

2. A machine for manufacturing tubular bodies comprising a coating table, means for guiding a strip of fabric over the table, a plurality of drying surfaces, means for guiding the fabric over the drying surfaces in succession, a forming mandrel, means for 10 rotating the forming mandrel and means for exerting a yielding pressure on the convolutions of fabric as they are wound upon the mandrel.

3. A machine for manufacturing tubular bodies comprising a coating table, means for guiding a strip of fabric over the table, a plurality of drying surfaces, means for guiding the fabric over the drying surfaces in succession, a forming mandrel, means for 20 rotating the forming mandrel, a carriage comprising a pressure plate, means for applying heat thereto and means for yieldingly forcing the pressure plate toward the forming mandrel.

25 4. A machine for manufacturing tubular bodies comprising a coating table, means for guiding a strip of fabric over the table, a plurality of drying surfaces, means for guiding the fabric over the drying surfaces in succession, a forming mandrel, means for 30 rotating the forming mandrel, and a carriage comprising a yieldingly supported pressure plate, means for applying heat thereto, means for forcing the carriage as a whole toward the forming mandrel and 35 adjustable means for restraining the last-named means.

5. A machine for manufacturing tubular bodies comprising a coating table, means for 40 guiding a strip of fabric over the table, a plurality of drying surfaces, means for guiding the fabric over the drying surfaces in succession, a forming mandrel, means for 45 rotating the forming mandrel, a carriage comprising a beam extending longitudinally of the forming mandrel, a pressure plate yieldingly supported on the carriage, heating apparatus adapted to heat the pressure plate, means for forcing the carriage as a 50 whole toward the forming mandrel and yielding means for restraining the forces exerted by the last-named means, whereby the pressure between the plate and the forming mandrel may be adjusted as desired.

55 6. A tube machine comprising a forming mandrel, a carriage near the surface and parallel to the axis of the forming mandrel, means for forcing the carriage toward the mandrel, a strap or cord yieldingly connected to the carriage and tending to sepa-

rate the carriage from the mandrel and means for adjusting the tension of the strap or cord.

7. A machine for manufacturing tubular bodies comprising a rotatively supported 65 forming mandrel, a carriage comprising a yieldingly supported pressure plate extending longitudinally of the mandrel, apparatus for supplying heat to the pressure plate, means tending to force the carriage 70 toward the mandrel, means for yieldingly restraining the carriage, and means for adjusting said restraining means.

8. A machine for manufacturing tubular bodies comprising a rotatively supported 75 forming mandrel, a carriage comprising a yielding supporting pressure plate extending longitudinally of the mandrel, apparatus for supplying heat to the pressure plate, means tending to force the carriage toward 80 the mandrel and means for yieldingly restraining the carriage, said means comprising a spring-connected tension strap or cord, a gathering reel therefor and means for adjusting the gathering reel to vary the 85 tension of the strap or cord.

9. A machine for manufacturing tubular bodies comprising a rotatively supported mandrel, a driving motor therefor, a floating carriage located near the surface and 90 parallel to the axis of the mandrel, weights tending to force the carriage as a whole toward the mandrel, retracting means for yieldingly opposing the action of the weights, and means for adjusting said re- 95 tracting means.

10. A machine for manufacturing tubular bodies comprising a rotatively supported mandrel, a driving motor therefor, a floating carriage located near the surface and 100 parallel to the axis of the mandrel, weights tending to force the carriage as a whole toward the mandrel, a pressure member yieldingly supported on the carriage, heating apparatus carried by the carriage and 105 adapted to supply heat to the pressure member, and retracting means comprising a strap or cord yieldingly connected to the carriage, and a gathering reel for the strap or cord, 110 and an adjusting worm for fixing the position of the gathering reel, whereby the action of the weights may be opposed to a greater or less degree.

In testimony whereof, I have hereunto subscribed my name this second day of May, 115 1912.

EMIL HAEFELY.

ARNOLD ZUBER.

It is hereby certified that in Letters Patent No. 1,171,609, granted February 15, 1916, upon the application of Emil Haefely, of Basel, Switzerland, for an improvement in "Apparatus for Manufacturing Insulation," an error appears in the printed specification requiring correction as follows: Page 3, line 77, claim 8, for the words "yielding supporting" read *yieldingly supported*; and that the said Letters Patent should be read with this correction therein that the same may conform to the record of the case in the Patent Office.

Signed and sealed this 21st day of March, A. D., 1916.
